UNITED STATES PATENT OFFICE.

FRANK BLANDO, OF NEW YORK, N. Y.

PRESS.

Application filed May 10, 1927. Serial No. 190,314.

This invention relates generally to improvements in presses, but specifically has to do with a lever press for forming artificial flower leaves.

- 5 One of the essential objects of the invention is to provide a device of the above-mentioned character, operable by the pressing of foot-treadles, one operation of one of said treadles resulting in the working-stroke 10 and simultaneously therewith the setting of the other of said treadles in a position to effect the raising of a presser bar, and conjunctively place in operative position the treadle effecting the initial working-stroke.
- 15 The invention is further featured by the provision of oscillatory levers, in the form of walking beams, operatively connected with each other, but individually joined to the foot-operating means aforesaid.
- 20 As will presently appear the device includes a presser bar adapted to reciprocate vertically in certain guiding means, and under the control of foot-treadles, the downward stroke of said presser-bar resulting in 25 the pressure of certain dies used in the manufacture of artificial flower leaves. This particular operation being called the working-stroke, obviously a greater amount of energy is required, or should be required, 30 and to this end the pivotal disposition of certain walking beams has been considered in order to secure a tremendous leverage distributed over a pair of levers.

Since the return of the presser bar to its 35 normal position does not require an undue amount of force, advantage is taken of this fact by splitting the work of one of the foot-treadles to the end that said pressure bar may be elevated to normal position 40 simultaneously with the elevation of the other foot-treadle to working position.

Other features of the invention will become apparent as the description proceeds, reference at this time being had to the accompanying drawings, wherein like characters of reference denote similar parts throughout the several views.

In said drawings:

Fig. 1 is a side elevation of my improved 50 press, the parts assuming their respective

positions during the working-stroke of the presser bar.

Fig. 2 is a plan view thereof.

Fig. 3 is a front elevation of Fig. 1, certain portions being broken away; and 55 Fig. 4 is a rear elevation thereof.

The device, though extremely efficient in operation, yet it comprises relatively few parts, simple in construction, and a glance at Fig. 1, discloses a standard 5, a presser 60 bar 6, a pair of levers or walking beams 7 and 8, foot treadles 9 and 10, cables 11 and 12 connecting respective treadles to said levers, and supporting means 13 for the device.

Said standard 5 embodies a base flange 14 suitably apertured at desired intervals for the reception of fastening devices 15 for firmly anchoring said standard to the supporting means 13. The standard is further 70 featured with lateral arms 16 and 17, each being provided with apertured bosses 18 and 19 respectively, at their upper ends, said bosses being preferably slotted to pivotally receive said levers 7 and 8. The presser bar 75 6, is squared at the lower portion, as indicated at 20, while the upper portion may be flattened at 21 for interfitting engagement with the forked end 7^a of said lever 7, the intermediate portion however being slidably engaged by the apertured boss 22 at 80 the outer end of an extension 23 of said standard 5.

As clearly shown in Figs. 1 and 2 of the drawings, lever 8 is provided with a forked 85 end 8^a for the pivotal reception of the other end of lever 7, the outer end of said lever 8 being apertured for securing one end of cable 12 attached to foot-treadle 9.

The other foot-treadle 10 is also operatively connected to the leverage just described through the medium of cable 11 having its upper end secured to an apertured lug 7^b of said lever 7.

In order to produce an efficient pressure, 95 featured by compactness of arrangement, I provide two sheaves 24 and 25, rotatably mounted on shafts 26 and 27 journaled in bracket 28, the upper end of said bracket being secured to the bottom of the top of 100

the supporting means 13, while its end may be bifurcated, as indicated in Figs. 3 and 4 for fastening to the rear legs of the supporting means, as shown at 30. It may also be pointed out the said standard 5 is longitudinally apertured, as shown at 5^a, for the reception of said cable or flexible element 11, the course of the aperture being, of course, continued through the top of the supporting means.

The position of the component parts of the press in Fig. 1 is at the end of the working stroke. That is, the foot-treadle 9 has been depressed and the pull exerted on the lever-
age via the cable 12 has shifted said leverage from the position indicated by broken lines to the position shown in full lines, thus pushing down said presser bar 6 to the dies to be engaged. However, at the same time a pull has been exerted on said cable or flexible element 11 by the rise of the leverage, said pull being communicated to the foot treadle 10 and elevating the same to the position indicated in Fig. 1. From the foregoing it should be apparent that the initial pressure on treadle 9 not only operated the presser bar 6, but also brought to operative position the other treadle 10 and further, a depression of the latter treadle positions the leverage as indicated by the broken lines and thus elevating said presser bar. Alternate pressure, therefore, on both treadles operates the presser bar and then resets it to inoperative position.

It should be carefully observed that the pivotal point of said lever 7 is positioned adjacent the forked end 7^a and that the connection of said cable 11 therewith is at a point somewhat remote from the pivotal connection, thus creating a decided mechanical advantage. This same general arrangement is true with respect to lever 8, but here the mechanical advantage is greater since rear of said lever is projected an appreciable dis-

tance from the pivotal connection of the 45 same. Thus, a pull on cable 12 is not only increased in power by the mechanical advantage of the lever 8 but also by the mechanical advantage of lever 7.

While the present is a disclosure of the 50 invention in its preferred form, it should be understood that the same is susceptible of modification within the spirit of the invention and the scope of the appended claims.

55

I claim:

1. In a press, a standard, levers pivoted to said standard and pivotally connected to each other, a presser bar connected to the shorter of said levers, a flexible member connected to the other end of said lever, a second flexible member connected to the other of said levers, and alternate means for operating said flexible members to lower and raise said presser bar.

2. In a press, a standard, levers pivoted to 65 said standard and pivotally connected to each other, a presser bar pivoted to the shorter of said levers, a flexible member connected to said levers adjacent their pivotal point, a second flexible member connected to 70 the other of said levers and means for alternately exerting a pull on said flexible members to lower and raise said presser bar.

3. In a press, a standard, levers pivoted to said standard and pivotally connected to 75 each other, a presser bar pivoted to one of said levers and slidably engaging said standard, a flexible member connected to said levers adjacent their pivotal point, a second 80 flexible member connected to the other of said levers, means for alternately operating said flexible members to lower and raise said presser bar and rotative elements guiding said flexible members and disposed intermediate their ends.

85 In testimony whereof I affix my signature.

FRANK BLANDO.
